UNITED STATES PATENT OFFICE.

AUGUSTUS A. BALL, JR., OF BROOKLYN, NEW YORK, ASSIGNOR TO MERGENTHALER LINOTYPE COMPANY, A CORPORATION OF NEW YORK.

TYPOGRAPHICAL CASTING-MACHINE.

1,076,343.

Specification of Letters Patent.

Patented Oct. 21, 1913.

Application filed December 26, 1911. Serial No. 667,742.

To all whom it may concern:

Be it known that I, AUGUSTUS A. BALL, Jr., a citizen of the United States, and a resident of Brooklyn, county of Kings, and State of New York, have invented a new and useful Improvement in Typographical Casting-Machines, of which the following is a specification.

My invention has reference to typographical casting machines, such for instance as linotype machines, wherein a slug or bar is cast in a slotted mold against a composed line of matrices, which is presented temporarily to the front of the mold and serves to 10 form the type characters on the edge of the slug. In this class of machines, as represented for example in U. S. Letters Patent to O. Mergenthaler, No. 436,532, the slug is delivered from the mold by an ejector blade, 15 which advances from the rear and moves the slug before it out of the mold and into a receiving galley.

In order to adapt the machine for producing slugs of different lengths, the mold slot 20 is made variable in length by the use of interchangeable filling pieces or liners, such as are shown for instance in U. S. Letters Patent to G. A. Bates, No. 618,554. When the length of the mold slot is thus changed, 25 the ejector should be also changed, and this is effected by detaching it and substituting another of a width corresponding to the new length of the slot.

In practice it occasionally happens that 30 an attendant, through ignorance or carelessness, will substitute a wide ejector without inserting a short liner, or that he will insert a long liner without changing the ejector. In such case, when the ejector advances, it 35 will contact with the inner end of the liner and drive it forward. As the liner is ordinarily provided with a transverse rib which is seated in a groove in the mold body, the result will be the breakage of the expensive 40 mold, due to the strength of the liner and the great leverage exerted thereby under such conditions.

The aim of my invention is to prevent accidents of this character, and this is effected 45 by the provision of a member which is adapted to yield in the event of undue strain thereon. Preferably, the liner is the member selected for such improvement, and more specifically the result is secured by lessening 50 its resistance, so that it will be moved or

bent by the advancing ejector without injury to the more expensive mold or to the ejector blade.

I have herein shown my invention as applied by way of example in a preferred form, 60 and obviously many changes and variations may be made therein without departing from its spirit. I therefore desire it to be distinctly understood that I do not limit myself 65 to any specific form or embodiment except in so far as such limitations are specified in the claims.

Referring to the drawing: Figure 1 is a perspective view of a mold having my invention applied thereto; Fig. 2 is a perspective view of the liner detached; Fig. 3 is a top plan view of the mold with the cap detached and illustrates the manner in which an ejector of too great width acts upon the 70 yielding liner.

Referring to the drawing, the mold consists of the body portion A, the cap B secured thereto, and liners interposed between the body and cap, whereby the slot D may be regulated both as to length and height, 80 in the manner well understood in the art and as substantially illustrated in the Bates patent previously mentioned. In order to prevent the breakage or bending of the expensive mold or of the ejector blade E, in the 85 event that the latter is too wide to pass through the mold slot D, I provide a yielding member, which in the specific example shown is the liner C. This liner in most respects is substantially the same as the one 90 illustrated in the Bates patent, it being formed with a slot C³ and with a transverse rib C², which latter engages in a corresponding groove in the mold body. This rib serves as a means for determining the longitudinal 95 adjustment of the liner and also for preventing the liner from turning or twisting horizontally. If therefore the ejector blade E be too wide to pass through the mold slot 100 D, and therefore contacts with the liner, ordinarily and due to the strength of the latter and the considerable leverage exerted thereby, the mold itself will be deformed or broken. It is therefore preferable to form the liner so that it will yield and be bent in 105 the event of undue strain being imparted thereto, and this result I secure by recessing it, as at C', at a point inside of the rib C², to provide an integral and permanently 110 weakened portion which is yieldable in the

event that sufficient pressure be exerted on an edge of the liner.

The operation of the parts is clearly shown in Fig. 3, it being noted that the advance of the ejector blade E acts merely to bend the liner, instead of allowing the latter to exert its destructive leverage upon the mold in the manner previously indicated. It should be noted that this weakening or 10 recessing of the liner does not otherwise affect its functions, as at the rear side thereof it presents a continuous surface of the ordinary extent and of sufficient strength to close tightly any holes in the pot mouth 15 which may lie behind it.

As before indicated, the broad idea of the invention is the provision of a yielding member for the purposes specified, and obviously its selection, location and construction may be varied in many ways that will 20 suggest themselves to those skilled in the art.

Having thus described my invention, its construction and mode of operation, what I claim and desire to secure by Letters Patent 25 of the United States is as follows:

1. A mold liner consisting of an integral structure formed of fracturable material and having in one edge a permanent recess extending inwardly toward the opposite

edge, thereby providing a permanent reduced portion which is yieldable whenever the liner is engaged by an ejector. 30

2. A mold liner consisting of an integral structure formed of fracturable material and having in one edge a permanent recess 35 extending inwardly toward the opposite edge, thereby providing a permanent reduced portion which is yieldable whenever the liner is engaged by an ejector, said liner being provided with a transverse rib at one 40 side of and adjacent the recess.

3. In a typographical casting machine, the mold comprising a body portion, a cap, and a mold liner consisting of an integral structure formed of fracturable material 45 and having in one edge a permanent recess extending inwardly toward the opposite edge, thereby providing a permanent reduced portion which is yieldable whenever the liner is engaged by an ejector. 50

In testimony whereof I hereunto set my hand this 13th day of December, 1911, in the presence of two attesting witnesses.

AUGUSTUS A. BALL, JR.
